UNITED STATES PATENT OFFICE.

JOHN ROYDEN PEIRCE, OF NEW YORK, N. Y., ASSIGNOR TO ROYDEN MARBLE MACHINE COMPANY, OF NEW YORK, N. Y., A CORPORATION OF NEW JERSEY.

STONEWORKING-MACHINE.

No. 862,938.

Specification of Letters Patent.

Patented Aug. 13, 1907.

Application filed October 31, 1904. Serial No. 230,863.

To all whom it may concern:

Be it known that I, JOHN ROYDEN PEIRCE, a citizen of the United States, residing in the borough of Manhattan, city, county, and State of New York, have invented certain new and useful Improvements in Stoneworking-Machines, of which the following is a specification.

The improved machine of this invention is designed especially for coping stone, that is to say, for cutting 10 slabs into sizes for wall facings or the like. The machine is also adapted to cut stone in various other ways.

The machine, though preferably used with a rotating carborundum wheel, is adapted also for use with cutters of various other styles.

15 The accompanying drawings illustrate a machine embodying the invention.

Figure 1 is a cross-sectional view showing the cutting head and its supports in front elevation. Fig. 2 is a side view. Fig. 3 is a plan made in two separate parts. 20 Figs. 4 and 5 are vertical, transverse sections of the cutter head in two different positions.

An important feature of the machine, independently of the particular sort of cutter used, is the construction hereinafter defined by reason of which it is adapted to 25 cut in two directions. Thus, without moving the stone from its holder, lengthwise and transverse cuts may be made to cut the rough slab into a rectangular coping. These two movements are preferably obtained by utilizing the longitudinally-moving bed to secure cuts 30 in a longitudinal direction, and holding said bed stationary while moving the cutter across it to cut in a transverse direction (the cutting edge of the cutter being preferably adjustable about a vertical axis).

Referring to the embodiment illustrated, the holder 35 for the stone is in the form of an ordinary planer bed A to which the stone may be clamped, and which receives longitudinal movement by means of a screw-threaded shaft B which is connected at one end by means of a worm C with a cross shaft D. Extending across the 40 bed is a frame which carries the cutter and which is composed of uprights E and horizontal guides F along 45 which moves the cutter head, which is indicated as a whole by the letter G. The cutter head is carried directly in a carriage H which slides upon the guides F of the cross head and which receives its transverse movement from a screw-threaded shaft J passing through a suitably threaded portion of the carriage and fixed at its ends in the uprights E. The head G is vertically adjustable in the carriage H by means of a 50 grooved shaft K working in a spindle worm-wheel L which drives a similar worm-wheel L' which is internally threaded and causes an up-and-down movement of the vertical screw shaft M fastened in a cross-bar N at the rear of the head. The guides F are in fact the 55 edges of a hollow cross-bar O in which the shafts J and

K lie. The worm-wheel L is carried upon a rearwardly-extending arm P of the carriage H, so that it moves with the carriage. The worm-wheel L' is mounted between a pair of cross-bars Q likewise projecting from the carriage H, and for the same reason. The shafts J and K are provided, for purposes of adjustment, with hand-wheels R and S at the front of the machine.

When it is desired to make a longitudinal cut, the stone is clamped upon the bed in the usual way, the hand-wheel R is turned to give the desired lateral adjustment to the cutter T, and the hand-wheel S is turned to adjust it vertically. The cutter is then held with rigidity, which is an important matter, and in exactly the desired line and level. The cutter is then rotated at a high rate of speed by means of a pulley U on the 70 cutter shaft V, and a belt W which runs to the top of the head G and over a pair of pulleys X and Y to any suitable driving drum pulley Z arranged overhead and at a sufficient distance to permit the desired vertical and lateral adjustments of the cutter. The usual longitudinal movement of the bed A will then be effected by pushing the lever a in the direction of the arrow, Fig. 1, which, by means of a link b and lever c, will throw the clutch block d into position to engage the shaft D and move the bed accordingly. The clutch and driving connections may be of any suitable style, the clutch block d being splined, for example, upon a power shaft e.

For making a transverse cut, means are provided for applying power to the shaft J to move the cutter across and through the stone. With a rotating cutter such as 85 T, it is essential also that the cutter be adjusted to the direction of the cut. Accordingly the shaft V of the cutter is mounted in a block f which is held in the lower end of the cutter head G by means of a circular rib g rotating in a corresponding groove in the lower end of 90 the cutter head. The cutter head is provided with a movable section h for permitting the insertion of the block f. The amount of angular movement of the block f is unlimited; and it may be desirable to work it at various angles, but for ordinary purposes the only 95 transverse cut desired will be one at right angles to the longitudinal cut. In order to determine the right-angle position the block f is provided with a pin j adapted to fit into either one of two sockets k in lugs k' at right angles to each other upon the 100 front of the cutter head, the locking pin j being carried by a hand-lever l which is held upward by a spring m. To turn the cutter it is only necessary to press down the hand lever l, and swing the cutter until the pin j clicks into the next socket k. The necessary power may be 105 obtained by means of a sprocket on the end of the shaft J opposite the hand-wheel, that is to say, at the back of the machine, and a sprocket chain n extending from said sprocket to another sprocket upon a short sleeve o surrounding the power shaft e. The sleeve o and the 110

clutch *d* have adjacent clutch faces; so that when the lever *a* is thrown in one extreme position it drives the bed *A* in a longitudinal direction, and when the lever is thrown in the opposite extreme position it drives the shaft *J* and the cutter in a transverse direction.

As stated above, the details of the clutches are not of importance, but it is preferred to arrange the clutches so as to obtain most easily the operations described. For example, the power shaft *e* may be driven in one direction by means of a conical pulley *p*, the shaft being supported in bearings *q*. The movement in the reverse direction is obtained from a pulley *r*, both pulleys *r* and *p* being loose on the shaft *e*. A second clutch block *s* is splined to the shaft *e* and arranged to engage either the pulley *r* or the pulley *p* according as it is shifted in one direction or the other by means of a rod *t* supported at one end in a bearing *q* and connected at its other end to one arm of a bell-crank-lever *u*, the other arm of which is connected by means of a link *v* to a hand lever *w* at the center and front of the machine.

No claim is made in the present application to the cutting of the stone by means of a thin wheel of agglomerated carborundum acting in the manner of a circular saw, the same being claimed in my application Serial No. 378,741, filed June 13, 1907.

25

What I claim is:

1. A stone cutting apparatus including, in combination, a cutter adapted to move transversely, a holder for the stone adapted to move longitudinally, a common power shaft, and a clutch which clutches the cutter or the holder alternately to said power shaft.

2. A stone cutting apparatus including, in combination, a cutter head *G*, a cutter shaft *V*, a block *f* carrying said cutter shaft and adjustable about a vertical axis in the lower end of said cutter head, a shaft *J* for moving said cutter head laterally, and means for clutching said shaft *J* to a power shaft.

35

In witness whereof, I have hereunto signed my name in the presence of two subscribing witnesses.

JOHN ROYDEN PEIRCE.
